UNITED STATES PATENT OFFICE.

JOHN F. ROBB, OF CLEVELAND HEIGHTS, OHIO, ASSIGNOR, BY MESNE ASSIGNMENTS, TO KOEHRING COMPANY, OF MILWAUKEE, WISCONSIN, A CORPORATION OF WISCONSIN.

AUTOMATIC CONTROL MEANS FOR MIXERS.

Original application filed August 11, 1916, Serial No. 114,481. Divided and this application filed October 27, 1920. Serial No. 419,974.

To all whom it may concern:

Be it known that I, JOHN F. ROBB, a citizen of the United States, residing at Cleveland Heights, in the county of Cuyahoga and State of Ohio, have invented certain new and useful Improvements in Automatic Control Means for Mixers, of which the following is a specification.

This invention appertains to the art of machines designed especially for mixing concrete, or the like, and in its practical embodiment contemplates the provision of certain peculiar automatic means whereby as a charge of aggregates to be mixed is introduced into the mixing machine, water from a suitable source of supply is caused to flow into the mixer until a predetermined required amount is received by the latter, whereupon the flow of the water is automatically cut off.

The invention involves further the uniting of the automatic water supply means aforesaid with certain automatic mechanism by which a timer controls the operation of a discharge chute for the mixer, the said chute being prevented from discharging until a predetermined time such as is necessary for a complete and proper admixture of the aggregates, has elapsed. By the use of this invention in conjunction with said chute and batch time controlling mechanism the water supply means is put into operation simultaneously with the setting into action of the timing mechanism, there being common control devices for the two. The operation of both the water supply means and the timing mechanism is initiated under the control of a loading skip or hopper by which the aggregates are elevated and placed within the mixer, this control being advantageous for obvious reasons.

In the accompanying drawings—

Figure 1 is a side elevation of a mixing machine of a type today known as the "Koehring paver", the equipment including means made in accordance with the invention;

Figure 2 is a view in elevation showing the box or compartment containing the timing and counting mechanism, and showing the driving connections with the mixing drum;

Figure 3 shows on an enlarged scale the

locking and throw-over device for the discharge chute; and

Figure 4 is a view illustrating the water supply actuating means and common operating device for said means and the timer.

This application is a division of my application Serial Number 114,481, filed August 11, 1916 and patented March 1, 1921, No. 1,370,497 for concrete distributing machine.

Referring to Figure 1 of the drawings, the mixing drum is designated at A and the charging skip or loader at B. The skip B is adapted to be raised by power driven mechanism under the control of a clutch lever 1. Said operating mechanism is not described being immaterial to this invention.

As the skip B reaches the dotted line charging position of Figure 1, it contacts with the uppermost arm of the lever 2 the materials in the skip gravitate into the mixer A, and the said action likewise results in a tripping or actuation of the three-armed lever 2 mounted on the framework of the machine and connected by a rod 3 with a lever 4 disposed above the box 5 which encloses the main parts of the timing mechanism. The lever 4 is connected with a rod 6, see Figure 2, forming a part of the mixture time controlling mechanism, said rod 6 being encircled by a spring 7 disposed in the box or casing 5 upon which the rod 6 slides vertically.

On the rod 6 is a projection 8 adapted to engage and move a lever 9. When the lever 2 is tripped by the engaging action of the skip B in abutment therewith, the rod 6 is raised until the projection 8 thereon engages the adjacent offstanding portion of the lever 9. In this way the rod 6 is held up by the lever 9, the spring 7 being compressed. The action of the projection 8 engaging the lever 9 rocks said lever on its pivot 9', carried by the back of the box 5, thereby causing the lever 9 to exert a pull on a link 10 connected therewith and connected with a bell crank lever 11 pivoted in the box 5. The lever 11 is connected with a bar 12 on which is mounted a sliding toothed timing member 13.

Normally a spring 14 coacts with the lever 9; also normally the projection 8 bears

5 downwardly on the right hand end of the bar 12 to hold the member 13 with its teeth disengaged from the worm 15 carried by the shaft 16, which worm is constantly driven through connecting beveled gears 17 and 18, the former on the shaft 19 and the latter on the shaft 16.

10 The shaft 19, seen in Figures 1 and 2, has a spur gear 20 in mesh with one of the gear rings 21 surrounding the drum or mixer A, the parts 16, 17, 18, 19, and 20 being thus driven from the mixer itself.

15 In the box 5 is a dog 22 pivoted to a lever 23 which is connected by a link 24, the lower end of which, see Figure 3, is attached to a pivoted catch 25. The catch 25 engages a stud 26 on a lever 27 carried by the shaft 28 by which the discharge chute C is actuated. Said shaft 28 is suitably connected 20 with the discharge chute C to throw the latter from a normal non-discharging position to its discharging position, the type of chute being such as generally illustrated in U. S. Letters Patent of Philip Kochring, No. 25 1,126,487, patented January 26, 1915.

30 In the path of the uppermost of the arms of the lever 2 is an actuating bar 29 adapted to slide horizontally on the frame-work of the machine through the projection of suitable guide means 30. This bar 29 carries an upwardly yieldable gravitational dog 31 adapted to engage a stud 32 upon a valve lever 33 connected with a valve 34 located at a suitable point in the length of a water 35 pipe 35. The pipe 35 leads from a water tank 36 mounted on the frame-work of the machine, to a point just within the charging end of the mixer as seen in Figure 1. One 40 end of the bar 29 is adapted to be impinged by the lever 2 every time the latter is rocked on raising of the skip B.

45 Upon actuation of the bar 29 by the lever 2 it will be apparent that the dog 31 is caused to engage the stud 32 to rock the lever 33 and open the valve 34. In this manner as the mixer A is charged with the aggregates from the skip B a predetermined quantity of water enters the mixer drum. At a certain point in the movement of the 50 bar 29 the dog 31 passes over or escapes the stud 32 so that the valve lever 34 may be gradually returned to its valve closing position under the action of a spring 35' connected with said lever.

55 The parts 33, 34, and 31 are adapted to be operated so as to close the valve 34 after the necessary quantity of water is admitted to the mixer. The bar 29 remains in its actuated position so long as the lever 2 remains in its actuated position but will return to its normal position under the action of a spring 36 when the lever 2 is released at the conclusion of the required time for effecting the mixing operation. As the bar 29 60 returns to its normal position the dog 31

yields freely upwards and freely passes over the stud 32 in an obvious manner.

65 It is understood that I do not wish to be confined to the particular automatic means for controlling the opening and closing of the water supply valve 34 since any suitable means may be employed for the above purpose within the purview of the invention.

70 The actuation of the lever 2 not only operates the water valve control device as above described but results in lifting of the rod 6 raising the projection 8 which passes by the dog 22 at which stage water is being admitted to the mixer drum and the aggregates to be mixed have been introduced also into said drum. Furthermore the movement of the projection 8 has caused the timing member 13 to engage with the worm 15, said worm causing the timing member to move toward the outer end of the bar 12. The time required for the adjustable tripping arm 37 on the timing member 13 to move against the lower end of the lever 9 represents the required period for effecting 90 a thorough admixture of the materials in the mixer. When the arm 37 engages the lower end of the lever 9, the latter is rocked and disengaged from the projection 8 whereupon the projection with the rod 6 is forced 95 downwards by the spring 7. When the projection 8 moves downwards a buffer spring 9" cushions the drop of the projection as it strikes the member 12, said spring being interposed between the parts 12 and 10, the heel of the same engages a shoulder on the dog 22 and shifts the latter downwards tilting the lever 23 and raising the rod 24. The upward movement of the rod 24 pulls the catch 25 from engagement with the stud 26, see Figure 3, whereupon the discharge chute C is automatically released and shifted to its discharge position by means of a spring 100 motor 38 connected with a shaft 28 by which the chute C is actuated. The chute C may 110 be restored to its nondischarging position in any suitable manner, as set forth in the application above identified now matured into Letters Patent #1,370,497, issued March 1, 111 1921.

112 It may be noted also that the downward restoring movement of the projection 8 on the rod 6 restores the parts 4, 3, and 2 to their normal positions, the projection itself 113 striking the adjacent end of the bar 12 and lowering the same. The spring 14 forces the lever 9 outwards at its upper end, shifts the link 10 and lever 11 and lowers the inner end of the bar 12 when the projection 8 is released, whereby the timing member 13 114 is lowered and disengaged from the worm 15 and remains so disengaged until the rod 6 is raised again by the actuation of the skip B. A spring 39 pulls the timing member 13 115 back to normal position in which it is shown 120

in Figure 2, on lowering of the bar 12. A counter D has its arm 40 arranged to be actuated to register a count each time the lever 9 is rocked to the R as shown in Figure 2.

Having thus described my invention, what I claim as new and desire to obtain by Letters Patent is:—

1. In combination, a mixer, a discharging device therefor, automatic means for moving said discharging device from non-discharging to discharging position, a charging device for introducing materials into the mixer, means intermediate said charging device and the said automatic means whereby one is controlled from the other, water supply means associated with said mixer, and means intermediate the charging device and said water supply means whereby the action of the latter is controlled from the charging device.
2. In combination, a mixer, a discharging device therefor, water supply means for the mixer, mechanism common to said discharging device to control the discharging action thereof and to said water supply means for also controlling the action of the latter, and a charging device for the mixer adapted to control the operation of the last mentioned mechanism.
3. In combination, a mixer, a discharging device therefor, a charging device therefor, mechanism adapted to control the discharging device so as to prevent discharging action thereof and controlled from the charging device to cause the discharging device to assume discharge position at a predetermined time, and water supply means for supplying a predetermined quantity of water to the mixer controlled from the above mentioned mechanism.
4. In combination, a mixer, water supply means therefor, a discharging device for the mixer, and an actuator common to said water supply means and to the discharging device for controlling the water supply action of the water supply means and for initiating a subsequent discharging action of the discharging device.
5. In combination, a mixer, water supply means therefor, a discharging device for the mixer, an actuator common to said water supply means and to the discharging device for controlling the water supply action of the water supply means and for causing discharging of the discharging device subsequently on lapse of a predetermined mixing period, and comprising a lever and operating connections between said lever and the water supply means and the discharging device, and a charging device for the mixer adapted to operate said lever as an incident to each charging action of said charging device.
6. In combination, a mixing machine, a timing mechanism for determining the time
- required for mixing of aggregates by said machine, means for supplying water to the aggregates, a charging device for the mixing machine, and means operable by the charging device for setting into action said timing mechanism and the water supply means.
7. The mixing machine construction including the water supply means and timing mechanism for the mixing operation, with a charging device to set in action the timing mechanism and water supply means.
8. Means as claimed in claim 7 combined with the timing mechanism functioning with the valve operating mechanism.
9. In a mixing machine, a timer controlling the time required for proper mixing in the machine, a water admission control device for the mixer, and means common to the timer and water control device for operating them.
10. In combination, a mixer, a discharging device therefor, means to move the discharging device from non-discharging to discharging position, motor means to actuate the last named means, water supply means for the mixer, a batchmeter controlling the action of the motor means aforesaid so that the discharging operation takes place immediately upon conclusion of a minimum effective period of mixing of the aggregates in the mixer, and a charging device, and means for causing the water supply means to feed a required amount of water to the mixer at the time the said charging device charges the dry aggregates into the mixer, to insure the introduction into the mixer of both liquid and dry aggregates at the commencement of a mixing operation, and mechanism to set the batchmeter into action as the charging device charges the mixer to predetermine the time of action of the discharge from the time when all the aggregates enter the mixer.
11. In a mixing machine, a timer controlling the time required for proper mixing in the machine, a water admission control device for the mixer, and means to control charging of the machine for controlling the operations of the timer and water admission device.
12. In a mixing machine, in combination, a timer controlling the time required for proper mixing in the machine, a water supply means, means to control admission of water from said supply to the mixer, a device for operating the timer and said water admission control device, and means controlling the charging of the mixer and adapted to control the operating device for the timer and water admission control means.
13. In combination, a mixer, a discharging device therefor, means to move the discharging device from non-discharging to discharging position, motor means to actuate the last named means, water supply

- means for the mixer, a batchmeter controlling the action of the motor means aforesaid so that the discharging operation takes place immediately upon conclusion of a minimum effective period of mixing of the aggregates in the mixer, and a charging device, and means controlled by the charging device for causing the water supply means to feed a required amount of water to the mixer at 10 the time the said charging device charges the dry aggregates into the mixer, to insure the introduction into the mixer of both liquid and dry aggregates at the commencement of a mixing operation, and mechanism 15 to set the batchmeter into action operated by and as the charging device charges the mixer to predetermine the time of action of the discharge from the time when all the aggregates enter the mixer.
14. In a mixing machine, in combination, 20 a timer for controlling the proper mixing period of the machine, a water admission control device for the machine, a lever, operative connections intermediate said lever and the timer, and the lever and water admission control device, and means for controlling the charging of the machine adapted to operate said lever.
15. Means as set forth in claim 14 combined with a discharge for the mixer controlled from the timer. 25

In testimony whereof I affix my signature.

JOHN F. ROBB.
